MECHANICAL PENCIL

Samuel Kannuer, New York, N. Y., assignor to
Spencerian Pen Company, New York, N. Y., a
corporation of New Jersey

Application January 19, 1939, Serial No 251,711

10 Claims. (Cl. 120—17)

This invention relates generally to mechanical pencils and more particularly to mechanical pencils of the magazine type, that is mechanical pencils in which a compartment is provided for the reception of leads which are automatically fed into an operative position as required.

More particularly, also, my invention relates to a mechanical pencil having a lead advancing means of the clutch type, in which the lead is advanced stepwise into a protruding position.

Among the objects of my invention is the provision of a simple, compact, effective and inexpensive construction for a mechanical pencil of the clutch type in which the lead is advanced stepwise by a reciprocating movement of an operating member.

These objects and such other objects as will hereinafter appear or be pointed out, are attained by the illustrative embodiment of my invention shown in the drawing, in which—

Figure 1 is a longitudinal sectional view through a pencil constructed according to my invention; showing the lead and the parts of the pencil in a position of use;

Figure 2 is a similar view, with portions broken away and with the cap of the pencil removed, and the lead and the parts of the pencil being shown in the position they occupy at the end of a lead advancing adjustment and prior to a return of the parts into the operative position of Figure 1.

Figure 3 is a transverse sectional view taken substantially on the line 3—3 of Figure 1, looking in the direction of the arrows; and

Figure 4 is a section taken on line 4—4 of Figure 1 on the level with the top of the head 26.

Referring now to the drawing for a detailed disclosure of my invention, it will be observed that the body of the pencil comprises a barrel 10 having a pair of interthreaded bushings 11 and 12 set into one end thereof and forming a chamber 13 therewithin for a purpose that will presently appear. The inner bushing 11 is shown abutting against a shoulder 14 in the bore of the barrel 10 which prevents its outward movement while the bushing 12 is shown abutting against the end 15 of the barrel 10.

The outer end of the bushing 12 has a threaded extension 16 thereon which is shown as carrying a tapered nose piece 17 that constitutes the end of the pencil.

It will be observed that the outer surfaces of the end portion of the barrel 10, the bushing 12 and the nose piece 17 merge into each other to form a tapering extremity for the pencil and

will further be observed that the bushings 11 and 12 and the nose piece 17 are provided with aligned bores, through which a lead L may pass. The bores of the respective pieces vary at different portions thereof so as to accommodate various parts to be hereinafter described.

The bore of the nose piece 17 is of restricted diameter at its end portion as shown at 18. Its inner portion is wider as shown at 19 and serves to accommodate a lead retaining member or friction tube 20, which may be in the form of a tube of resilient material having a nose portion of restricted diameter adapted to bear against the lead L and which is shown as slotted as at 21 to provide resilient jaws. The portion 19 of the bore is made sufficiently large to permit expansion of these jaws.

The lead retaining member 20 is shown as passing through a restricted portion 22 of the bore of the bushing 12 by which it is centered, 20 and through a widened portion 23 of the bore of said bushing into the bore of a sleeve 24 mounted for sliding movement in the said bore portion 23 and provided with a hollow head 25 positioned within the aforementioned chamber 13.

The hollow in the head 25 is shown as receiving therewithin the enlarged end portion 26 of a collet 27 provided with resilient jaws 28 adapted to grip a lead passing through the bore of the 30 collet, when they are pressed thereagainst. It will be observed that the lead L—1 shown between the jaws 28 is separate from but aligned with the lead L of which the end protrudes from the end of the pencil. When the jaws 28 grip 35 it and advance it, it therefore pushes the lead L outward, and in effect acts as though it were integral therewith, in this respect. While it would be quite feasible to use pieces of lead of a length such that they would be gripped by the 40 jaws 28 while their lower end portion protrudes from the pencil, there is an advantage in using short pieces which may be carried in a magazine of lesser length than where long pieces are used, and the overall length of the pencil may therefore be kept within desired limits. There is further less danger of breakage of leads when they are short.

While I have shown three jaws 28 (see Figure 3) it will be understood that any desired number 50 may be used; I have however found in practice that three jaws are very satisfactory.

The head 26 is shown as tapered and as undercut so as to provide a shoulder 29 adapted to abut against complementary shoulders in the hollow 55

of the head 25 whereby withdrawal of the head 26 is prevented. In order to permit of the insertion of the head 26 into the head 25, the latter may be slotted into several portions, which are adapted to spread as the tapered head 26 is inserted therebetween. By making the head 25 of resilient material it will snap into place over the head 25. A sleeve 30 may then be slipped over the head 25, thereby preventing separation of the portions thereof and locking the collet 27 to the sleeve 24.

As will be more clearly understood as the description proceeds the sleeve 24 might be made integral with the collet 27 without affecting the operation of the device. However practical manufacturing considerations make the construction shown desirable for many reasons, among which may be mentioned ease of assembly and the advantage of using different materials for the collet 27 and the sleeve 24.

In order to cause the jaws 28 of the collet 27 to grip the lead L-1 when it is desired to advance the lead L-1 I have shown an arrangement comprising a sleeve 31 slidable within the barrel 10 and carrying sleeves or collars 32, 33 and 34 suitably secured thereto as for example by swaging portions of the sleeve 31 so as to form beads at appropriate points. The collar 32 is the lowermost one of these, and it surrounds and is slidable on the collet 27 and serves as a seat for one end of a spring 35, the other end of which seats on the bushing 11. The spring 35 serves to urge the sleeve 31 and the parts it carries upward, that is away from the nose portion of the pencil, into a position shown in Figure 1, which position is determined in part by considerations that will appear hereinafter.

The collar or sleeve 33 is shown as having a tapered bore 36 the walls of which are adapted to engage cam portions 36a provided on the outside of the end portions of the jaws 28 of the collet 27 and to cause them to move inwardly and to grip the lead L-1 when the sleeve 33 is moved into the position shown in Figure 1. It will be obvious that the collar 33 cannot move upwardly beyond this position, and since it is carried in fixed relation to the sleeve 31, this position of collar 33 also determines the limiting position of the sleeve 31 in an upward direction. 50 When the collar 33 moves downwardly from its position in Figure 1 it will release the jaws 28, which move outwardly because of their resiliency, thereby releasing the lead.

In addition to the opening of the jaws 28 because of their resiliency I have shown means for positively effecting such opening. Such means is illustrated as a tubular member 37 provided with a tapered nose portion 38 and slidably mounted within the collar 34. It is urged against the jaws 28 by a spiral compression spring 39 located in a recess 40 provided between the collar 34 and the member 38, suitable abutments being provided on the tubular member 37 and the sleeve 34 against which the ends of the spring 39 bear. 60 The upper end of the sleeve 31 serves as a magazine for extra leads M and this magazine is provided with a closure 41, which may conveniently be in the form of a cup and may serve to carry an eraser 47 therein. In order to limit the extent to which the closure 41 may be inserted into the sleeve 31 I have provided means in the form of a bead 42.

The member 37 has a dual function, namely that just described and also the function of agitating the leads M in the magazine, when, as will

hereinafter appear, its upper end moves thereinto, so that the lead will more readily drop into the passageway for the leads, the upper end of which is constituted by the bore of the "agitator" 37.

A cap or sleeve 43 is shown as having one end portion seated over the sleeve 31 and extending into the barrel 10. A bead 44 on the sleeve 31 serves to limit the extent to which the cap 43 can be inserted into the barrel and at the same time serves as a shoulder by which downward movement of the cap 43 will be transmitted to the sleeve 31 for the purpose of causing the advance of the lead in the bore of the pencil. The upper end of the cap 43 is closed by a member 45. A clip 46 is shown carried by the cap; this is conveniently made integral with the member 45.

In Figure 1 the parts of the pencil are shown in what may be called their normal position, and the pencil is ready for use. While the cap 43 is shown in place in the barrel 10, it is to be observed that it may be removed if it is desired to use the eraser 47, or if for other reasons it is desired to use the pencil without the cap.

If it is desired to load the magazine with a supply of leads this is readily done by removing the closure 41 and with it the eraser 47 and inserting the desired number of leads M. It will be observed that owing to the inclined upper walls of the sleeve 34 and the tubular member 37 and their stepwise arrangement, the leads automatically feed in succession into the bore of the member 37 as soon as its upper end is clear.

It will be observed that in Figure 1 the sleeve 31 and the collars 32, 33 and 34 are in their uppermost positions, being urged upwardly by the spring 35, and the collar 33 has carried the collet 27 with it and has closed the jaws 28 thereof against the lead L-1. At the same time the jaws 28 limit the further upward movement of the collar 33 and consequently of all the parts carried by sleeve 31, because of the fact that the collet 27 has been forced into its uppermost position, which is determined by the head 25 of the member 24 striking the upper wall of the chamber 13. The agitator 37 is inactive.

The lead L is maintained in position by the lead L-1 which prevents its inward movement, since the lead L-1 is itself locked against inward movement, and the member 24 holds the lead L against accidental outward movement by its frictional grip. It will therefore be obvious that with the parts of the pencil as shown in Figure 1, the pencil is ready for use.

When it is desired to advance a lead the sleeve 31 must be pushed inward to the maximum extent. This may be done by pushing on the cap 43, if it is in place, as in Figure 1, or by pushing on the eraser 47, if the cap has been removed, as in Figure 2. In the latter figure the sleeve 31 is shown pushed inward, and the normal position of the eraser has been indicated in dot and dash lines, while its pushed-in position has been shown in full lines.

The effect of the inward pushing of sleeve 31, as shown in Figure 2, is to move the collars 32, 33 and 34 downward carrying the collet 27 and the member 24 with them, until the lower end of the member 24 reaches the limit of its downward movement by striking the shoulder 48 of the bushing 12. When this occurs the member 24 and the collet 27, which are interlocked against relative axial movement are brought to a stop, but the sleeve 31 continues its inward movement, with the result that the nose portion 75

38 of the member 37 enters between the jaws 28 of the collet 27 and spreads them, thereby releasing the lead L-1. As a result of the resistance of the collet 27 to further movement the agitator 37 is brought to a stop and the spring 39 is compressed until a point is reached at which it stops the downward movement of the collar 34 and with it the sleeve 31 and all the parts carried by it. This relative movement between the sleeve 31, and particularly the part 34 carried by it, and the agitator 37, causes the upper end of the latter to project into the magazine and thereby causes movement of some of the leads M in relation to others, which movement has the effect of assuring the entrance of one of the leads M into the bore of the pencil whenever the lead L-1 has moved sufficiently to clear the upper end of the bore.

When the jaws 28 of the collet 27 are spread, 20 the head L-1 is released and the advancing movement thereof and of the lead L ceases. The sleeve 31 is now released and the spring 35 causes it to return to its normal position of Figure 1. As it moves into said position it carries the collet 27 with it, but since the jaws 28 are open the lead L-1 is not retracted. When the head 25 strikes the upper wall 49 of the chamber 13 the collet 27 is brought to a stop, but the movement of the sleeve 31 and the parts 30 it carries, and in particular the collar 33, continues. The collar 33 thereby exerts a wedging action and closes the jaws 28 and forces them against the lead L-1. This results in ultimately bringing the collar 33, and with it the sleeve 31, to a stop in the position shown in Figure 1.

As a result of this manipulation the lead L has been advanced through a distance represented by the space between the dot and dash line 50 of Figure 2 and the end of the lead L 40 of the pencil. Should further projection of the lead be desired the operation of pushing the sleeve 31 inward must be repeated.

The advantages of the various features described hereinabove will now be further pointed out.

First of all it will be observed that the construction I have described is extremely simple and reliable in operation, there being no intricate mechanisms or parts requiring delicate adjustment that will readily get out of order.

Secondly, assembly of the parts is an extremely simple matter. As can be readily understood from the drawing the parts 31, 37, 27, 32, 33, 34 and 39 are first assembled as a unit to which are added the spring 35 and the bushing 11. The sleeve 24 then has its head 25 snapped in place over the head 26 of the collet 27, after which the sleeve 30 is slipped over the head 25 and the parts thereby secured against separation. The assembly unit so obtained may then be slipped into the barrel from above, after which it is locked to the barrel by threading the bushing 12 into the bushing 11. The assembly of the few remaining parts is so obvious that no description is needed.

It will further be noted that the passage or bore through which the leads move from the magazine, is continuous, and has no breaks therein into which leads or fragments thereof can move laterally and thereby obstruct the bore and prevent proper functioning of the mechanism.

Control of the leads entering the lead passage takes place near the entrance to the passage so that very shortly after a lead enters

the passage it is gripped by the collet jaws 28 and acts on all leads below it. This construction makes next to impossible the situation in which a lead gets jammed at the upper end of the passage while the lead or leads in the lower portions of the passage are fed outward. There being nothing to move or force the jammed piece, the pencil will become useless.

Attention may also be called to the advantages of the two-piece construction of the nose 10 portion of the pencil, which makes possible an enlargement of the bore 19 to permit the jaws of the friction tube 20 to move freely, while at the same time the bore 22 may be restricted to prevent undesired lateral movement of the 15 friction tube 20.

While I have herein disclosed by way of illustration one embodiment of my invention, it will be understood that the same may be embodied in many other forms without departing from the spirit thereof, as will be obvious to those skilled in the art, and that the disclosure herein is by way of illustration merely and is not to be interpreted in a limiting sense, and that I do not limit myself other than by 25 the scope of the subjoined claims.

Having thus described my invention and illustrated its use, what I claim as new and desire to secure by Letters Patent is:

1. In a magazine lead pencil comprising a hollow barrel, a passageway adapted to receive a lead therein, and provided with an opening for discharging said lead, means for frictionally retaining the lead in said passageway, and means for advancing the lead in said passageway a predetermined distance, said means comprising a collet having limited movement in the barrel and provided with spring jaws adapted to engage a second lead axially aligned with said first lead, and operating means for the jaws of said collet comprising a member slidably in the bore of said barrel and adapted to move into a normal position when released, said member carrying means for moving said resilient jaws inward and for releasing said jaws so that they are free to open when said operating member is pushed inward, and said member also carrying means for positively spreading said spring jaws, said spreading means being movable relatively to said operating member and being urged into a predetermined position in relation thereto by resilient means.

2. In a magazine lead pencil comprising a hollow barrel, a passageway adapted to receive a lead therein and provided with an opening for discharging said leads, means for frictionally retaining the lead in said passageway, and means for advancing the lead in said passageway, a predetermined distance, said means comprising a collet having limited movement in the barrel and provided with spring jaws adapted to engage a second lead in said passageway axially aligned with said first lead, and operating means for the jaws of said collet comprising a member slidably in the bore of said barrel, resilient means for causing said member to move into a normal position when it is released, said member carrying means for moving said resilient jaws inward against the lead when said operating means is released and for releasing said jaws so that they are free to open when said operating member is pushed inward, and said member also carrying means for positively spreading said spring jaws, said spreading means being movable relatively to said operating member and being urged into a predetermined 70 position in relation thereto by resilient means.

mined position in relation thereto by resilient means.

3. In a mechanical pencil, a barrel, a chambered member positioned at one end of said barrel and comprising a pair of threaded interfitting parts one of which is positioned entirely within the barrel and the other of which forms an extension of the barrel, a tip portion threaded to the second of said members, said members having a passageway therein, adapted to receive leads, resilient means adapted to grip a lead positioned in said passageway so as to maintain it in position therein, a collet having its lower part comprising two parts interlocked against relative axial movement and having an enlarged head extending into said chamber of the chambered member and having limited movement therein and its upper part extending into the barrel and provided with resilient spring jaws adapted to grip a lead positioned between said jaws, a tubular member slidable in said barrel and having a collar at its end portion surrounding said collet, a compression spring positioned between the inner end of said chambered member and said collar and tending to move said operating member away from said chambered member, means for operating the jaws of said collet comprising a tubular member with a tapered bore surrounding said collet and adapted to engage its jaws positioned in adjacency to said collar, means for retaining said tubular member in adjacency to said collar, and means for spreading the jaws of said collet slidably mounted within said retaining means.

35 4. In a mechanical pencil, a barrel, means provided with jaws adapted to grip a lead mounted for limited sliding movement in said barrel, and operating means mounted for movement in said barrel and provided with means to close or to release said jaws as it moves longitudinally in said barrel, and means adapted to spread said jaws carried by said operating means.

45 5. In a mechanical pencil, a barrel, means provided with jaws adapted to grip a lead mounted for limited sliding movement in said barrel, and operating means mounted for movement in said barrel and provided with means to close or to release said jaws as it moves longitudinally in said barrel, and means adapted to spread said jaws mounted for movement on said operating means.

55 6. In a mechanical pencil, fixed parts including an outer casing, a collet mounted for movement in said casing and comprising two members interlocked against relative axial movement, one of said members having means thereon for gripping a lead, and the other of said members being provided with means adapted to engage fixed parts of the pencil so as to limit the movement of said collet, and said members having aligned axial bores adapted to receive a lead therein.

65 7. In a mechanical pencil, fixed parts including an outer casing, a collet mounted for movement in said casing and comprising two members interlocked against relative axial movement, one of said members having means thereon for gripping a lead, and the other of said members being provided with an enlarged head adapted to be

received in a chamber in the frame of said pencil and adapted to engage fixed parts of the pencil so as to limit the movement of said collet, and said members having aligned axial bores adapted to receive a lead therein.

8. In a mechanical pencil, a member provided with jaws adapted to grip a lead, means for causing said jaws to close, and means for causing said jaws to open carried by said jaw closing means.

9. A magazine pencil comprising a barrel, operating parts at one end of the barrel providing a passageway therein for leads, said passageway opening to the exterior of the pencil for the extrusion of leads therefrom, and means for causing movement of the leads in said passageway having portions extending through the other end of the barrel and projecting outwardly therefrom, whereby said means may be manipulated to slide longitudinally in said barrel and to cause the advancement of leads positioned in the passageway, said means having a hollow portion adapted to receive a plurality of leads and said hollow portion communicating with said passageway, said passageway being of a length greater than the maximum length of the leads adapted to be received in said hollow portion, a collet provided with spring jaws adapted to grip a lead situated in said passageway, frictional means for resisting the movement of the leads out of the passageway, means for causing the jaws of said collet to grip a lead in said passageway, said means being operated by the movement of said operating means, and means carried by said operating means but movable relatively thereto for causing the positive opening of the jaws of said collet at a predetermined point.

10. A magazine pencil comprising a barrel, operating parts at one end of the barrel providing a passageway for leads and opening to the exterior of the pencil for the extrusion of leads from said passageway, and means for causing movement of the lead in said passageway having portions extending through the other end of the barrel and projecting outwardly therefrom, whereby said means may be manipulated to slide longitudinally in said barrel and to cause the advancement of leads positioned in the passageway, said means being provided with a hollow portion adapted to receive a plurality of leads and said hollow portion communicating with said passageway, said passageway being of a length greater than the maximum length of the leads adapted to be received in said hollow portion, a collet provided with spring jaws having inclined outer surfaces adapted to grip a lead situated in the passageway, frictional means for resisting the movement of leads out of the passageway, means for causing the jaws of said collet to grip a lead in said passageway, said means being provided with a tapered bore adapted to engage the inclined outer surfaces of said jaws and being operated by the movement of said operating means, and means carried by said operating means but movable relatively thereto for causing the positive opening of the jaws of said collet at a predetermined point.

SAMUEL KANNER.
